US0D1112243S

(12) **United States Design Patent** (10) **Patent No.:** **US D1,112,243 S**
(45) **Date of Patent:** **** Feb. 10, 2026**

(54) **DISPLAY SCREEN OR PORTION THEREOF
WITH GRAPHICAL USER INTERFACE**

- (71) **Applicant:** **Sleep Number Corporation**, Minneapolis, MN (US)
- (72) **Inventors:** **Stacy Stusynski**, Blaine, MN (US); **Russell Hampton**, San Francisco, CA (US); **Kelsey Kong**, San Francisco, CA (US); **Kristen Elizabeth Swenby**, Blaine, MN (US); **Julie Elepano**, Minneapolis, MN (US); **Carol Lynn Herman**, Minneapolis, MN (US)
- (73) **Assignee:** **Sleep Number Corporation**, Minneapolis, MN (US)
- (**) **Term:** **15 Years**
- (21) **Appl. No.:** **29/979,340**
- (22) **Filed:** **Dec. 18, 2024**

CLAIM

The ornamental design for a display screen or portion thereof with graphical user interface substantially as shown and described.

DESCRIPTION

The file of this patent contains at least one drawing/photograph executed in color. Copies of this patent with color drawing(s)/photograph(s) will be provided by the Office upon request.

FIGURE is a front view of a display screen or portion thereof with a graphical user interface showing the claimed design.

The broken lines in the FIGURE show a display screen or portion thereof, and form no part of the claimed design.
